PROCESS OF AND APPARATUS FOR CONTINUOUS BLENDING, FOR A PREDETERMINED QUALITY, OF LIQUIDS HAVING DIFFERENT SPECIFIC GRAVITIES

Walter C. Holmes, Indianapolis, Ind.

Application May 29, 1933, Serial No. 673,498

17 Claims. (Cl. 221—96)

This invention relates to a process of blending liquids, such as gasoline, of different specific gravities to obtain a resultant liquid having predetermined qualities.

5 The chief object of this invention is to facilitate and expedite the supplying of gasoline, and the like, having a predetermined quality to distributing tank trucks, which gasoline is blended by the mixture of gasolines of different gravities 10 and which mixing or blending may be accomplished during the time that the receiving element, such as the tank truck, is available for filling, although the discharge may be collected in a reservoir for subsequent discharge to the 15 tank trucks or distributing devices.

Heretofore it has not been possible to discharge directly from a plurality of underground storage tanks, liquids from each and blend the same and directly discharge the blended liquid to the 20 distributing device, such as the tank truck.

The present invention is directed to a process for accomplishing this purpose, thereby eliminating the necessity of a plurality of reservoirs for different qualities of blended liquids demanded 25 by different customers, and the resultant saving in reservoir space, reservoir cost, and the saving in the amount of liquid is enormous, all of which is accomplished by practicing the process set forth hereinafter more specifically in detail.

30 The chief feature of the invention consists in continuously and simultaneously abstracting from a plurality of underground reservoirs during a given time interval, predetermined amounts of liquids therefrom and utilizing the same abstracting device to mix and discharge as a blended mixture the composite liquid, and if desired, directly to a distributing device such as a tank truck.

Another feature of the invention consists in 40 the particular control arrangement whereby the predetermined set-standard of the blended liquid may be maintained during the continuous operation of supplying a predetermined amount of blended liquid to any given receiving device.

45 The invention contemplates pumping from a header independently connected to a plurality of underground sources of liquids at the same or different levels and containing liquids of different qualities, the sources having a controlled communication with the header and discharging the liquid to the header. The header discharge is passed through a meter for registering the amount of the blended liquid. The predetermined quality of the blended liquid discharged 50 is continuously determined by a visible gauge de-

vice which is so arranged that it is continuously supplied with the blended liquid. The discharge from said device is returned to the source of power or pump. The indicating device, therefore, always indicates the quality of the liquid 5 being discharged through the meter.

A suitable device for practicing the process is more or less diagrammatically disclosed herein, and the drawing includes an elevational view of apparatus suitable for utilizing the process. 10

In the drawing one form of apparatus suitable for practicing the process is exemplified, and in the figure of the drawing 10 indicates the ground line, 11 a plurality of underground storage tanks provided with ground exposed filling members 12, 13 connected to the tanks by the pipes 13. The liquid is supplied to each tank from different tank cars containing liquid of a predetermined quality, that is, for example, gasoline of a certain specific gravity. For example, the left hand tank shown 20 in the drawing may be supplied with natural gasoline, which is about 88° specific gravity. This is casing head gasoline. The second tank immediately to the right thereof may be supplied with what is known as "standard motor fuel" 25 or gasoline which has a 60° specific gravity and the other tanks may be supplied with gasoline of different specific gravities or may comprise additional tanks for casing head or motor gasoline. Each tank includes a discharge line 14 30 which terminates as at 15 near the bottom of the tank. The numeral 16 indicates the liquid level in each of the reservoirs or tanks 11.

A header 17 communicates with the discharge end of each line 14 and each line 14 includes a 35 manually operable regulating valve 18. The header includes a discharge line 19 and included therein is a check valve 20 to prevent return flow of the gasoline. The line 19 at its discharge end connects to a pump 21, the latter having a 40 discharge 22 that discharges to a meter 23. The meter has the discharge line 24. It may be arranged to discharge into a reservoir mounted above the ground or overhead for gravity discharge to a distributing supply device, such as 45 a tank truck. Usually, however, line 24 is arranged to discharge directly to the tank truck, thereby eliminating the necessity of storage space. As is well known, tank trucks contain approximately three or more compartments and 50 if the customer or wholesaler of gasoline sends an order for three different grades of gasoline, the same can be rapidly blended for the customer and discharged to the respective compartments of the tank truck by means of this device, the 55

meter indicating the actual amount of each blend received by each compartment in the tank truck.

A line 25 having a Pitot tube inlet 25a departs from line 22 between the pump 21 and the meter 23. This line includes a check valve 26 that prevents return flow to line 22. The line 25 also includes a manually operable control valve 27. Line 25 discharges to a chamber 28 which has a transparent portion, and herein the same is shown as 10 a cylindrical side wall. The discharge from the chamber 28 is at the level indicated by the line 29 and the same is appreciably below the top of the chamber. The pipe 30, in this form of the apparatus, extends through the top of the chamber 15 and extends downwardly therein and has its inlet end at the elevation indicated by the line 29. The pipe 30 includes therein a check valve 31 to prevent the return flow of the liquid into the chamber 28 and pipe 30 discharges to the pipe 19 as at 20 32. The chamber 28 is sealed except for connections 25 and 30.

The operation of the apparatus is as follows:—

A predetermined blend is desired. The engineer knows from his gasoline property tables just 25 how much or what fraction of gasoline of different characteristics must be included in the unit amount in order to produce the unit amount of blended gasoline having the particular properties desired. By the aforesaid it is to be understood 30 that specific gravity of the liquids is not the whole determining factor. The so-called anti-knock factor is important and different gasolines of approximately the same specific gravity have different anti-knock properties. The same also applies to the end points and intermediate points of 35 the respective gasolines that are stored in the reservoirs or tanks 11.

The engineer determines what percentage of 40 each unit of the liquid is to be supplied from two or more reservoirs 11, and the operator of the apparatus, who may be the tank truck driver or the plant attendant, operates valves 18 included in the designated lines 14, to provide the desired communication between each of the selected 45 tanks or reservoirs 11 and the header 17. The pump 21, which is usually electrically motor driven, is then started and the suction of the pump pulls into the header through the lines 14 that have been opened, the respective amounts of 50 liquid from each reservoir being supplied to the header, in accordance with the opening of the respective valve 18. For example, one valve 18 may be entirely opened and the other valve, or valves, but partially opened, depending on 55 whether only a second reservoir is to supply liquid or two or more reservoirs are to supply additional liquid. If a valve is fully opened it is usually the one that controls the motor fuel gasoline tank and the blending is usually made by adding to 60 this supply.

When the pump 21 is started, suction is applied to the header and thence to the intakes 15 of the respective lines 14, the valves 18 of which are 65 opened to the desired degree. The discharge from the pump flows immediately through line 22 to the meter and at the same time discharges a portion of the blended liquid into line 25 through check valve 26 and a restricted amount is supplied to the chamber 28, the restriction being determined by the degree of opening of valve 27. Initially, this valve may be fully opened so that the chamber 28 will immediately fill slightly above the level 29 and then the surplus discharges by way of line 30 from the chamber. Line 30, as 75 before mentioned, has its discharge end 32 com-

municating with the suction side of the pump 21 and communicates with line 19 so that the pump exerts a suction on line 30 and it takes but a very few seconds for the operator to adjust the position of valve 27 so that the level of the liquid in the 5 chamber 28 is maintained substantially at the position indicated by the numeral 29.

Mounted in the chamber 29 is a gasoline specific gravity gauge or hydrometer 40 and as will be apparent from the aforesaid, the liquid in the 10 chamber 28 is continuously and instantaneously that corresponding to the liquid that is being then discharged through the meter and thence discharged by line 24. All the operator has to do is to watch the gauge 40 and see that the level of the 15 liquid in chamber 28 always is that level indicated at 29 and the gauge 40 indicates the gravity that has been predetermined for the blended liquid desired to be produced. Sealing of chamber 28 equalizes the pressure therein to such an extent 20 that the float 40 does not rise up with the increase in pressure of the liquid flowing into the chamber, or at least to such a degree that it would materially affect the hydrometer reading.

If for any reason the gravity runs higher in the 25 blended liquid than that desired or ordered, the operator opens the valve 18 controlling the lower gravity supply line 14 and thus permits an increasing amount of lower gravity gasoline to be supplied to the mixture. The operator watches 30 the hydrometer 40 during this adjustment.

It might be here noted that due to climatic conditions, and the like, to produce a blended gasoline of a predetermined quality, many factors enter and the same valve setting will not produce 35 the same blended quality of gasoline. Consequently, for each specific run, the quality must be checked and continuously checked through constant observation of the hydrometer or gauge and that is the only guarantee that the predetermined 40 quality in the blended liquid will be obtained.

Should the blended gasoline run lower in its specific gravity than that desired, then the valve 18 of the line 14 communicating with a supply of higher specific gravity, such as the casing head 45 or natural gasoline supply, would be correspondingly opened until the desired specific gravity in the blended discharge is obtained.

It is apparent that the hydrometer indicates at 50 all times the exact gravity condition of the blended discharge.

A further feature of the invention, as applied to the apparatus and process, consists in the fact that not only does the pump constitute a source of power for continuously supplying to the chamber 28 and exhausting therefrom the previously supplied liquid so that the hydrometer will continuously indicate the quality of the discharge from line 24, but the pump in addition to serving as a source of power for lifting the liquid from 60 the underground storage tanks also serves as a mixer for completely mixing the various types of gasoline that are comprised in the blended liquid.

When the desired amount of liquid has been 65 blended and discharged to the receiving device, such as the tank truck, then the electric motor is stopped and all further operation ceases. The valves may then be closed or left open as desired. When a series of trucks are to be filled, all that is necessary is to stop the motor in order to permit 70 one truck to move from the loading station and an empty truck take its place. As before mentioned, different grades of blended gasoline and in the desired amounts, may be rapidly supplied without the requirement of extra storage space or 75

tanks or auxiliary mechanism for blending to the distributing devices or tank trucks.

It is to be here noted that the retailer who purchases gasoline from the wholesaler expects to receive gasoline of a certain quality and prices are based on the quality ordered. If a lower quality is shipped, the retailer receives many complaints from his customers or automobile operators as to the failure of the fuel to function as claimed, because gasoline of different specific gravities will function differently. The retailer, as a general rule, never complains about gasoline with a higher specific gravity than that which he has ordered. Casing head or natural gasoline is much more expensive than motor gasoline, as the respective terms have been used hereinbefore, so that with the industry operating at a very low percentage of profit, the blender and wholesaler of gasoline, if more than the required amount of natural gasoline is used, will find himself operating without any profit or at a loss whenever more than the minimum amount of casing head or natural gasoline is used in the blending.

When electrical control devices are applied the hydrometer mechanism, or similar mechanism which is responsive to the change in the specific gravity of the liquid in the chamber 28, will be so arranged that through direct or remote control devices, it will automatically control the movement of the valves 18 in the lines 14.

It is to be understood that temperature must be accounted for. For every 10° F. of temperature from the assumed standard (for example, 60° F.), the gravity is changed 1°—i. e., if the liquid temperature is 50° F., the gravity will be increased 1° above that determined for the desired blended liquid, if the liquid temperature is 70° F., the gravity is 1° less, etc.

Herein the chamber 28 communicates by line 41 with a thermometer well 43 supported at 42 and includes a sealed in thermometer 44. Any other suitable thermometer device may be provided and in certain instances a recording thermometer may be arranged to automatically shift the automatic specific gravity device to secure full automatic control.

Since the invention is primarily directed to the process of blending, the mechanism set forth herein before with respect to the automatic and remote control of the valves 18, is not illustrated nor is it believed the same is necessary, since remote control and the electrical operation of valves for opening and closing the same is per se as well known.

5 The invention claimed is:—

1. The process of continuously preparing a predetermined desired blended liquid from a plurality of sources of liquid, each having a predetermined gravity and other known qualities, comprising simultaneously pumping from each of a plurality of the selected sources, controlling the flow from each selected source to the pumping mechanism, discharging the pumpage from the selected sources to a receiver, and simultaneously with the pumping continuously supplying a portion of the discharge to a specific gravity indicating device and withdrawing the same therefrom by the pumping mechanism for continuously indicating the specific gravity of the blended discharge.

2. A process as defined by claim 1, characterized by the simultaneous mixing of the liquids by the pumping mechanism to form a uniformly blended discharge.

5 3. A process of continuously preparing a de-

sired blended liquid from a plurality of underground sources of liquid, each source containing a liquid having a predetermined gravity and other known qualities, comprising elevating to a common chamber or header, the liquid from a plurality of selected sources, individually controlling the individual flow from each source to the header, withdrawing the combined flows from the header by a pumping mechanism, simultaneously mixing the header discharged liquids in the withdrawal to form a uniformly blended discharge, continuously by-passing to a specific gravity indicating device a portion of the blended liquid, and withdrawing the by-passed portion of the liquid therefrom by means of the pumping mechanism.

4. A process of continuously preparing a desired blended liquid from a plurality of underground sources of liquid, each source containing a liquid having a predetermined gravity and other known qualities, comprising elevating to a common chamber or header, the liquid from a plurality of selected sources, individually controlling the individual flow from each source to the header, withdrawing the combined flows from the header by a pumping mechanism, simultaneously mixing the header discharged liquids in the withdrawal to form a uniformly blended discharge, continuously by-passing to a specific gravity indicating device a portion of the blended liquid, withdrawing the by-passed portion of the liquid therefrom by means of the pumping mechanism, and controlling the amount of liquid by-passed to continuously maintain a predetermined level of blended liquid in the indicating device, whereby the blended liquid in the indicating device at any instant is substantially that of the discharged blended liquid.

5. Apparatus for continuously preparing a blended liquid from a plurality of liquids having known properties to obtain predetermined properties in the blended liquid including in combination a plurality of individual liquid containing reservoirs, a discharge line from each, individual valve means in each discharge line, pumping mechanism having a single intake operatively connected to each of the individual discharge lines and a pump discharge, a meter connected to the pump discharge for measuring the flow or volume discharged by the pumping mechanism, a by-pass mechanism including a chamber adapted to receive a portion of the blended liquid discharged from the pump, means connecting said chamber to the pump discharge whereby the chamber is supplied with blended liquid and under pressure, and means arranged to maintain a predetermined liquid level in the chamber and connected to the pump intake whereby the pump continuously removes the by-passed pressure supplied liquid, and a specific gravity responsive device operatively associated with the by-pass chamber.

6. A device as defined by claim 5, characterized by the connection between the pump discharge and the by-pass chamber including other valve means for regulating the amount of liquid by-passed from the pump discharge.

7. Apparatus for continuously preparing a blended liquid from a plurality of liquids having known properties to obtain predetermined properties in the blended liquid including in combination a plurality of individual liquid containing reservoirs, a discharge line from each, individual valve means in each discharge line, pumping mechanism having a single intake op-

- eratively connected to each of the individual discharge lines and a pump discharge, a by-pass mechanism including a chamber adapted to receive a portion of the blended liquid discharged from the pump, means connecting said chamber to the pump discharge whereby the chamber is supplied with blended liquid and under pressure, and means arranged to maintain a predetermined liquid level in the chamber and connected to the pump intake whereby the pump continuously removes the pressure supplied bypassed liquid, and a specific gravity responsive device operatively associated with the by-pass chamber.

8. A device as defined by claim 7, characterized by the connection between the pump discharge and the by-pass chamber including other valve means for regulating the amount of liquid bypassed from the pump discharge.

9. Apparatus for continuously preparing a blended liquid from a plurality of liquids having known properties to obtain predetermined properties in the blended liquid including in combination a plurality of individual liquid containing reservoirs, a discharge line from each, individual valve means in each discharge line, pumping mechanism having a single intake operatively connected to each of the individual discharge lines and a pump discharge, a header interposed between the valve means and pumping mechanism intake and to which each of the valve controlled lines is adapted to discharge, a meter connected to the pump discharge for measuring the flow or volume discharged by the pumping mechanism, a by-pass mechanism including a chamber adapted to receive a portion of the blended liquid discharged from the pump, means connecting said chamber to the pump discharge whereby the chamber is supplied with blended liquid and under pressure, and means arranged to maintain a predetermined liquid level in the chamber and connected to the pump intake whereby the pump continuously removes the bypassed pressure supplied liquid, and a specific gravity responsive device operatively associated with the by-pass chamber.

10. A device as defined by claim 9, characterized by the connection between the pump discharge and the by-pass chamber including other valve means regulating the amount of liquid bypassed from the pump discharge.

11. Apparatus for continuously preparing a blended liquid from a plurality of liquids having known properties to obtain predetermined properties in the blended liquid including in combination a plurality of individual liquid containing reservoirs, a discharge line from each, individual valve means in each discharge line, pumping mechanism having a single intake operatively connected to each of the individual discharge lines and a pump discharge, a header interposed between the valve means and pumping mechanism intake and to which each of the valve controlled lines is adapted to discharge, a by-pass mechanism including a chamber adapted to receive a portion of the blended liquid discharged from the pump, means connecting said chamber to the pump discharge whereby the chamber is supplied with blended liquid and under pressure, and means arranged to maintain a predetermined liquid level in the chamber and connected to the pump intake whereby the pump continuously removes the pressure supplied bypassed liquid, and a specific gravity responsive device operatively associated with the by-pass chamber.

12. A device as defined by claim 11, characterized by the connection between the pump discharge and the by-pass chamber including other valve means for regulating the amount of liquid bypassed from the pump discharge.

13. Apparatus for continuously preparing a blended liquid from a plurality of liquids having known properties to obtain predetermined properties in the blended liquid including in combination a plurality of individual liquid containing reservoirs, a discharge line from each, individual valve means in each discharge line, pumping mechanism having a single intake operatively connected to each of the individual discharge lines and a pump discharge, a header interposed between the valve means and pumping mechanism intake and to which each of the valve controlled lines is adapted to discharge, a meter connected to the pump discharge for measuring the flow or volume discharged by the pumping mechanism, a by-pass mechanism including a chamber adapted to receive a portion of the blended liquid discharged from the pump, means connecting said chamber to the pump discharge whereby the chamber is supplied with blended liquid and under pressure, means arranged to maintain a predetermined liquid level in the chamber and connected to the pump intake whereby the pump continuously removes the bypassed pressure supplied liquid, and a specific gravity responsive device operatively associated with the by-pass chamber, and check valve means interposed between the pumping mechanism and the header and preventing return flow to the header and between the by-pass chamber and the pump discharge and preventing return flow to the by-pass chamber and the pumping mechanism intake preventing return flow to the by-pass chamber.

14. A device as defined by claim 13, characterized by the connection between the pump discharge and the by-pass chamber including other valve means regulating the amount of liquid bypassed from the pump discharge.

15. Apparatus for continuously preparing a blended liquid from a plurality of liquids having known properties to obtain predetermined properties in the blended liquid including in combination a plurality of individual liquid containing reservoirs, a discharge line from each, individual valve means in each discharge line, pumping mechanism having a single intake operatively connected to each of the individual discharge lines and a pump discharge, a header interposed between the valve means and pumping mechanism intake and to which each of the valve controlled lines is adapted to discharge, a by-pass mechanism including a chamber adapted to receive a portion of the blended liquid discharged from the pump, means connecting said chamber to the pump discharge whereby the chamber is supplied with blended liquid and under pressure, means arranged to maintain a predetermined liquid level in the chamber and connected to the pump intake whereby the pump continuously removes the pressure supplied bypassed liquid, and a specific gravity responsive device operatively associated with the by-pass chamber, and check valve means interposed between the pumping mechanism and the header and preventing return flow to the header and between the by-pass chamber and the pump discharge and preventing return flow to the by-pass chamber and the pumping mechanism intake preventing return flow to the by-pass chamber.

discharge and between the by-pass chamber and the pumping mechanism intake preventing return flow to the by-pass chamber.

16. A device as defined by claim 15, characterized by the connection between the pump discharge and the by-pass chamber including other valve means for regulating the amount of liquid by-passed from the pump discharge.

17. The process of continuously blending a plurality of liquids having different characteristics such as specific gravities into a blended liquid having a predetermined specific gravity consisting of pumping from a plurality of sources of liquids having different specific gravities predetermined proportions of each different liquid and simultaneously mixing the liquids so pumped in

the pumping thereof, continuously by-passing a relatively small proportion of the blended liquid to a specific gravity indicating device by continuously pumping a small proportion of the blended liquid to said specific gravity indicating device, simultaneously exhausting therefrom and redischarging to the blended liquid the small proportion of the blended liquid so by-passed, whereby the specific gravity of the blended liquid continuously and simultaneously deliverable is ascertainable, and controlling the proportions of the different liquids supplied in accordance with the variations disclosed by the specific gravity indicating device to continuously obtain a blended liquid of the desired specific gravity. 15
